(57) **CLAIM**

The ornamental design for a docking station for a thermostat as shown and described.

DESCRIPTION

FIG. 1 is an exploded perspective front view of a docking station for a thermostat shown in a configuration of use, in accordance with the present invention.

FIG. 2 is a perspective rear view of the docking station of FIG. 1, in accordance with the present invention.

FIG. 3 is a top view of the docking station of FIG. 1, in accordance with the present invention.

FIG. 4 is a bottom view of the docking station of FIG. 1, in accordance with the present invention.

FIG. 5 is a front view of the docking station of FIG. 1, in accordance with the present invention; and,

FIG. 6 is a right side view of the docking station of FIG. 1, in accordance with the present invention.

The broken lines are included for the purpose of illustrating portions of the docking station for a thermostat, as well as environment in FIG. 1, and form no part of the claimed design.
